RESTRANDING AND EXERCISING MITT

John T. Posey, 1739 Meadowbrook Road,

Altadena, Calif.

Filed Mar. 13, 1962, Ser. No. 180,937

4 Claims. (Cl. 128—25)

This invention relates to restraining mitts of the type used to limit the hand activity of patients in hospitals, rest homes, and the like, and is a continuation-in-part application of my copending U.S. application Serial No. 831,302, filed August 3, 1959, now abandoned.

The need often arises to prevent a patient from scratching, pulling out a catheter, nasal, or intravenous tube, etc., by limiting his hand activity and without causing discomfort. It is also desirable to have a mitt which can be manipulated to exercise an invalid patient's arm to prevent atrophying of the muscle and without discomfort to the patient. This invention provides a restraining mitt which meets both of these requirements.

Briefly, the restraining mitt of this invention comprises two sheets of material joined together to form a flat pocket shaped to fit around a patient's hand. The mitt also includes a wrist portion which opens from the pocket exterior to the interior to permit the mitt to be put on and taken off. At least one of the sheets carries means for rigidifying the pocket portion of the mitt so it resists bending.

The presently preferred embodiment of this invention includes a soft pad around the wrist portion to permit the mitt to be firmly secured to the patient's wrist with a belt and yet remain comfortable.

In one form of the mitt, the pocket portion is made rigid by a stiff plate, preferably of metal, secured between two folds of cloth on the palm side of the mitt. In another form of the mitt, the palm portion is made rigid by a plurality of longitudinal stiff stays disposed between two pieces of cloth on each side of the mitt. Preferably, all embodiments of the invention include holes through each of the sheets for air circulation about the patient's hand while confined in the mitt, and to facilitate the attachment of an exercising cord to the mitt. The cord can be gently raised and lowered either manually or automatically by a conventional crank arrangement which operates the cord on pulleys mounted over the patient.

The mitts of the invention are usually used in pairs, and each mitt includes an adjustable restraining strap adapted to be attached to the sides of a bed or the like and adjusted to determine the desired limit of movement of the patient's hands.

These and other aspects of the invention will be more fully understood from the following detailed description taken in conjunction with the accompanying drawings, in which:

FIG. 1 is a plan view, partially broken away, of one form of the mitt using a rigid plate on the palm side;

FIG. 2 is a view taken on line 2—2 of FIG. 1;

FIG. 3 is a plan view of another embodiment of the mitt using a plurality of longitudinal stays to provide the desired rigidity; and

FIG. 4 is a view taken on line 4—4 of FIG. 3.

Referring to FIGS. 1 and 2, a mitt 10 includes a first or back sheet 12 of cloth or other suitable material which preferably is flexible. The first sheet is generally fan-shaped having a relatively narrow wrist portion 14 which spreads out symmetrically into a wide pocket portion 16, and is secured by stitches 18 around its edges to a second or palm sheet 20 of identical size and shape so that a relatively flat pocket 21 is formed between the two sheets. As can be seen most clearly in FIG. 2, the wrist portions of the sheets include opposed wrist flaps 22, which are

2

not joined, to leave a wrist opening 24 through which the mitt is placed on and taken off a patient's hand.

A separate longitudinal loop 26 is secured to the outside of each wrist flap, and a draw belt 28 is disposed through the loops so that it can be drawn tightly and secured by a buckle 30 around the patient's wrist.

As FIG. 2 shows best, each wrist flap includes a sponge rubber pad 32 secured to the inside of each wrist flap by a retaining panel 34 stitched to a respective wrist flap.

A thin, flat rigid metal plate 36 is secured to the palm sheet in the pocket portion of the mitt by a piece of cloth 38 stitched to the outside of the palm sheet.

A first set of grommets 39 are secured through openings 40 in the back sheet at the end of the pocket 21 remote from the wrist portion. A second set of grommets 41 are secured in openings 42 through the palm sheet 20, plate 36, and cloth 38 under the first set of grommets. The openings through the grommets provide ventilation within the mitt. Preferably, the grommets in the first set are each collinear with a respective grommet in the second set. This facilitates looping an exercising cord 43 (FIG. 2) through a pair of collinear grommets.

The exercising cord is raised and lowered gently either by an attendant or else automatically by a conventional power-driven crank and pulley arrangement (not shown). The rigid plate supports the patient's hand as the cord is lifted, and thus spreads the force over a relatively large area to provide maximum comfort for the patient. Moreover, the flexible wrist portion of the mitt permits the patient's wrist to flex as the mitt is initially lifted by the exercising cord. Thereafter, the entire arm may be gently lifted. The reverse movement occurs as the mitt is lowered so the patient's entire arm may be fully exercised to prevent atrophying.

The exercising cord may also be used to secure the patient's hand for limited movement. However, preferably, an adjustable restraining strap 44 is looped through the belt 28 and adapted to be secured to the sides of a bed (not shown) in which the patient rests. The adjustable strap includes a buckle 45 to permit the strap to be adjusted to any desired length to set the required limit on the movement of the patient's hand.

Thus, with the restraining mitt shown in FIGS. 1 and 2, a patient's hand can be comfortably enclosed in a mitt which can be firmly secured to the patient's hand by the belt which fits around the wrist. The soft rubber pads in the wrist portion of the mitt prevent cutting and chafing of the patient's wrists, which often are thin and lack adequate natural protection from flesh. The rigid pocket of the mitt restrains the patient from acts with his hands which might delay his recovery or further impair his health, and at the same time, the mitt is ventilated and flexible at the wrist to provide some degree of freedom.

The restraining mitt 50 shown in FIGS. 3 and 4 includes a first or back sheet 52 of flexible material, which is generally fan-shaped and secured by stitches 54 around its edges to a second or palm sheet 56 so that a flat pocket 58 is formed between the back and palm sheets. The narrow portion of each sheet includes a respective wrist flap 60 to which is secured a separate respective sponge rubber pad 62 by a retaining panel 64 stitched to the inside of each wrist flap. A belt 66 passes around the outside of the wrist flaps and is disposed in separate longitudinal loops 68 attached to the outside of each flap. The wrist flaps are not stitched together across their ends so that an opening 70 is provided to open from the exterior to the interior of the mitt pocket whereby the mitt can be put on and taken off a patient's hand.

The back and palm sheets each include four longitudinal stays 72 which begin at the wrist portion and fan slightly outwardly to terminate short of the end of the

mitt. Each longitudinal stay is disposed in a separate slot 74 formed by stitches 76 which hold a stay panel 78 to the inside of each sheet. A separate transverse stay 80 is held across the closed end of the mitt pocket in a transverse slot 82 formed by stitches 84 across the closed end of the mitt.

A first series of three grommets 86 are provided in each of the sheets and open into the pocket part of the mitt at the inner ends of the longitudinal stays. A second set of three grommets 88 are in each of the sheets and open into the mitt pocket between the transverse stay and the closed end of the mitt.

An adjustable restraining strap 90 is looped through the belt 66 and provided with a buckle 92 to permit the length of the strap to be set to give the desired limited movement of the patient's hand.

The use of the mitt of FIGS. 3 and 4 is substantially the same as that shown in FIGS. 1 and 2. In both cases, the mitt provides for comfort around the patient's wrist, and will bend in the vicinity of the wrist to give some degree of freedom. However, the pocket portions of the mitt are held sufficiently rigid so that the fingers cannot bend the pocket part of the mitt, thereby preventing scratching and the removal of intravenous, catheter, and nasal tubes by the patient. At the same time, the pocket is sufficiently large so the fingers can be flexed within the pocket part of the mitt without bending it. This reduces the feeling of confinement and promotes blood circulation in the patient's hand.

As indicated previously, the mitt can be made of any suitable material, but preferably is of good quality cotton so it can be laundered by ordinary methods. The mitt exterior preferably has a tough finish, such as duck or canvas, while the interior is soft, such as flannel. It will also be obvious that the sheets forming the pocket mitt can be woven integrally, or joined together in any suitable manner other than by the stitches shown in the drawing.

I claim:

1. A hand-restraining mitt for a patient, the mitt comprising two sheets of material joined together around a portion of their edges to form a flat pocket part open at a wrist portion of the mitt to receive the hand of a patient, means carried by at least one of the sheets to rigidify the pocket portion of the said one sheet overlying the hand of the patient, the wrist portion of the sheets extending away from the pocket portion and beyond the

said rigidifying means to leave the wrist portion of the mitt flexible with respect to the said rigidified pocket portion, the sheets each having at least one separate hole through them, an exercising cord disposed through the holes, padding means encircling the wrist portion of the mitt, a longitudinal loop secured to the outside of the wrist portion, and a belt disposed through the said loop and around the outside of the padding and wrist portion for securing the mitt firmly to the wrist of the patient without chafing and to leave the wrist of the patient flexible.

2. A mitt according to claim 1 in which the holes in the sheets are collinear.

3. A mitt according to claim 1 in which the holes are at the opposite end of the mitt from the wrist portion.

4. A hand-restraining mitt for a patient, the mitt comprising two sheets of material joined together around a portion of their edges to form a flat pocket part open at a wrist portion of the mitt to receive the hand of a patient, a stiff plate carried by at least one of the sheets to rigidify the pocket portion of the said one sheet overlying the hand of the patient, the wrist portion of the sheets extending away from the pocket portion and beyond the plate to leave the wrist portion of the mitt flexible with respect to the said rigidified pocket portion, the sheets and plate each having at least one separate hole through them, an exercising cord disposed through the holes, padding means encircling the wrist portion of the mitt, a longitudinal loop secured to the outside of the wrist portion, and a belt disposed through the said loop and around the outside of the padding and wrist portion for securing the mitt firmly to the wrist of the patient without chafing and to leave the wrist of the patient flexible.
